OCTOPUS ROLLER TOY

George W. Dunbar and Paul L. Lubius, Nashville, Tenn.,
assignors to Kusan, Inc., Nashville, Tenn.

Filed May 27, 1975, Ser. No. 579,042

Term of patent 14 years

Int. Cl. D21—01

U.S. Cl. D34—15 B

FIG. 1

FIG. 2

FIG. 3

FIG. 1 is a perspective view of an octopus roller toy showing our new design;

FIG. 2 is a top plan view thereof; and

FIG. 3 is a front elevational view thereof.

The bottom of the toy is plain and unornamented.

We claim:

The ornamental design for an octopus roller toy, as shown and described.
